UNITED STATES PATENT OFFICE.

CLARENCE E. VAN DUZER, OF CLEVELAND, OHIO, ASSIGNOR TO THE BONNELL MANUFACTURING COMPANY, OF CLEVELAND, OHIO, A CORPORATION OF OHIO.

SWITCH OR TERMINAL BOX.

1,201,003.

Specification of Letters Patent.

Patented Oct. 10, 1916.

Application filed September 24, 1912. Serial No. 722,151.

To all whom it may concern:

Be it known that I, CLARENCE E. VAN DUZER, a citizen of the United States, residing at Cleveland, in the county of Cuyahoga and State of Ohio, have invented a certain new and useful Improvement in Switch or Terminal Boxes, of which the following is a full, clear, and exact description, reference being had to the accompanying drawings.

10 This invention relates to switch or terminal boxes which are used in interior electric light wiring for the housing or accommodation of electric light switches, and especially to that type of box that comprises 15 one or more like units, whereby the box thus constructed can accommodate any number of switches. Its objects are to provide a switch or terminal box of this character which is of simple construction, which is comparatively 20 cheap of production, which can be quickly and easily converted from a single switch box to a "gang" switch box for the accommodation of a number of electric switches without the use of special tools and which, either as a 25 single or a "gang" switch box, will afford an unobstructed cavity of maximum dimensions as compared with its exterior dimensions.

A further object is to provide a switch or terminal box which is equally as well 30 adapted for use in the wiring of buildings which have been completed prior to the installation of the electric wiring as for use in the wiring of new buildings.

These and further objects I attain by the 35 construction illustrated in the accompanying drawings forming a part hereof, wherein,

Figure 1 represents a left hand side elevation of my improved switch box, a portion 40 of the side plate being broken away to more clearly show the manner of its attachment to the body portion of the box; Fig. 2 a front elevation of a single unit constituting a switch box; Fig. 3 a right hand side 45 elevation thereof; Fig. 4 a plan view of the same; Fig. 5 a front elevation of a "gang" switch box, produced by the assembling of a number of the single units shown in the preceding figures; Fig. 6 a perspective view 50 of the eccentric screw which is used for attaching the side plates to a single switch box, or for connecting the various units together for producing a "gang" box; and

Fig. 7 a perspective view of the bracket for securing the switch box within a wall.

Describing by reference characters the 55 various parts illustrated in the drawings, the body of the switch or terminal box comprises generally a rear wall 1, top and bottom walls 2 and 3, respectively, and diagonal walls 4 which join the rear wall 1 with the top and bottom walls. Depending from the left hand edge of the top wall 2 and projecting upwardly from the left hand edge of the bottom wall 3 are lugs 5 and 6, respectively, each being provided with a hole, the one in the lug 5 being indicated at 7. Extending from the opposite edges of the top and bottom walls 2 and 3, and in transverse alignment with the lugs 5 and 6, are 60 lugs 8 and 9. These lugs are provided with bosses (the boss of lug 8 being indicated at 10) which are pressed outwardly from the central portion of the lugs a distance substantially equal to the thickness of the metal. 65

A side plate 11 is adapted to close the left hand side of the switch box and is provided with bosses 12 (similar to the boss 10 projecting from the lug 8) which are adapted to occupy the holes within the lugs 5 and 6 70 when the side plate is in place. The opposite side of the box is closed by a plate 13 having holes 14 near its upper and lower edges for the reception of the bosses projecting from the lugs 8 and 9. The side plates 11 and 13 75 are held in place by screws 15 which are threaded to the bosses projecting from the side plate 11 and from the lugs 8 and 9. The heads of these screws 15 are eccentric 80 with respect to the body portions thereof and the screws are eccentrically mounted within the bosses. The bosses and the screw heads are circular and the eccentricity of the screw body with respect to its head and the eccentricity of the screw hole with respect to 85 the lug are identical so that, in one position, the periphery of the screw head 15 may be coincident with that of the boss. It will be noticed, also, that the holes within the lugs 5 and 6 and the holes 14 in the plate 13 are 90 circular and somewhat larger in diameter than the heads of the screws 15.

From the foregoing facts it will be apparent that, when the screw heads are concentric with the bosses in which they are 105 mounted, the heads of the screws may be

passed through the holes within the lugs and the side plate 13 and the bosses inserted into the holes 7 and 14. When in this position, by the application of an ordinary screw driver, the screws may be turned a partial rotation, which is sufficient to draw them snugly against the adjacent face of the lug or plate, whichever the case may be, and because of the eccentricity of the screw form 5

10 an effective locking or securing means between the body of the switch box and the side plates.

In the assembling of a "gang" box, such as shown in Fig. 5, the right hand side plate 15 of the left hand unit is dispensed with; both side plates of the intermediate unit and the left hand side plate of the right hand unit are removed.

The lugs 8 and 9 of the left hand unit are 20 secured to the lugs 5 and 6 of the intermediate unit, and the lugs 8 and 9 of the intermediate unit are secured to the lugs 5 and 6 of the right hand unit in the same way that the side plates 11 and 13 are attached 25 to the body portion of the switch box which has been previously disclosed. This affords a very quick and convenient method of producing a "gang" box from a plurality of units, and a screw driver is the only necessary tool for the assembling.

A bracket 16 is attached to the top and bottom of my switch box by screws 17, for the securing of the switch box within a wall. In the construction of new buildings which 35 are to be fitted with switch boxes of the character herein described, substantial blocks are secured to the joist in a horizontal position and spaced far enough apart to accommodate the switch box. The brackets 40 16 are secured to these blocks by nails or screws which pass through the holes 18 within the longer section 19 of said brackets. Since these brackets are secured to the top and bottom walls of the switch box 45 some distance to the rearward of the front edge, the usual lathing and plastering may be accomplished without difficulty and, because of the dimensions of the brackets 16, the front of the box will be flush with the 50 surface of the wall.

Where it is desired to use my switch or terminal box in connection with the electric wiring that may have been installed without reference to its employment, I secure the 55 box in place by use of the brackets 16, but I reverse their positions, placing the shorter sections 20 in a vertical position and securing the brackets to the top and bottom walls of the switch box by passing the screws 17 60 through the holes 18 in the longer sections 19 thereof. The holes in the brackets are made of key-hole shape to obviate the necessity of removing the screws completely when reversing the brackets. When in the position just described, because of the dimen-

sions of the brackets the front of the box will be flush with the surface of the wall when the rear faces of the sections 20 of the brackets are placed against the face of the lathing.

Ears 21 which project from the top and bottom walls 2 and 3 and in substantially the plane of the front of the switch box are provided for the purpose of securing the usual face plate of a switch to each unit, 75 and this face plate will support the switch proper; but, to avoid confusion in the drawings and to aid in a clearer understanding of the construction of the switch box proper, I have omitted a showing of these parts. 80

It will be noted that the particular arrangement of lugs enables the securing means for one end of a "gang" box to be concealed within the body of the box.

The word "box" as employed in the claims 85 is not to be limited to a single unit having the side plates applied thereto, but is used (except where the language limits it to the unit or "gang" type) in a generic sense.

Having thus described my invention, 90 what I claim is:

1. A box for the purpose described comprising a body portion having holes, side plates having bosses adapted to occupy said holes, and means movably mounted upon the 95 bosses and adapted to be moved into a position to overlie the adjacent part of the body portion when the bosses occupy said holes whereby said side plates may be secured to the body portion.

2. A box for the purpose described comprising a body portion having holes therein, side plates having fixed bosses which are adapted to occupy said holes, and means eccentrically mounted upon said bosses to lock 105 the side plates and body portion together.

3. A box for the purpose described comprising a body portion having circular holes therein, side plates having fixed circular bosses which are adapted to occupy said 110 holes, and means eccentrically mounted upon said bosses to lock the side plates and body portion together.

4. As an article of manufacture, a body portion having, adjacent each side thereof, a pair of lugs projecting toward each other from opposite walls thereof, the lugs at one side of the body having perforations therethrough and the lugs at the opposite side having outwardly projecting bosses corresponding in shape to the perforations in the former lugs.

5. As an article of manufacture, a hollow body having, adjacent each side thereof, a pair of lugs projecting into the interior of the body, one pair of lugs having circular perforations and the other pair having circular bosses adapted to fit in the perforations of the lugs of an adjacent body.

6. As an article of manufacture, a body

portion having, adjacent each side thereof, a pair of lugs, one pair of lugs having holes therein and the other pair having bosses transversely alined with and complementary to said holes.

7. A box for the purpose described comprising a body portion having a lug provided with a boss, a side plate having a hole adapted to receive said boss, and means carried by the lug and arranged eccentrically with respect to the hole in the side plate, for locking the lug and side plate together.

8. As an article of manufacture, a body portion having a lug projecting from one side thereof and into the interior of the body and provided with a hole and having a lug

projecting from the opposite side thereof and provided with a boss of substantially the same size and conformation as the hole.

9. A box for the purpose described comprising a body portion having lugs projecting inwardly from opposite sides thereof and bosses on said lugs, a side plate having openings adapted to receive said bosses, and means on said bosses for locking the said plate and lugs together.

In testimony whereof, I hereunto affix my signature in the presence of two witnesses.

CLARENCE E. VAN DUZER.
